UNITED STATES PATENT OFFICE.

HANS SUMMA, OF SCHWARZENBACH-ON-THE-SAALE, GERMANY.

HAIR-PIN.

No. 839,791.

Specification of Letters Patent.

Patented Dec. 25, 1906.

Application filed June 27, 1906. Serial No. 323,584.

To all whom it may concern:

Be it known that I, HANS SUMMA, manufacturer, a subject of the King of Bavaria, German Empire, residing at Schwarzenbach-on-the-Saale, in the Kingdom of Bavaria, German Empire, (whose postal address is 15 Saalstrasse,) have invented new and useful Improvements Relating to Hair-Pins, of which the following is a specification.

10 The present invention has for its object a hair-pin with crossed arms.

Contrary to that which is the case with known constructions of hair-pins with crossed arms in accordance with the present invention the crossing is not obtained by bending the arms at an angle; but the arms continue beyond the point of intersection in a straight line and are bent obliquely at the ends in a certain manner. Further, the two arms 20 present resiliency toward each other at the place of intersection and the obliquely-bent ends are bent in the direction in which this resiliency is exerted. In addition, these oblique bends correspond to the direction in 25 which the two arms are yieldingly pressed together, so that when the pin is inserted its opening in overcoming the spring action at the point of intersection is facilitated to permit of the passage of the hair seized by it.

30 By this means numerous advantages are attained. Owing to the fact that when inserting the pin as a result of the coöperation of its bent ends and the place of intersection the pin is caused to turn automatically, the place 35 of intersection is to some extent opened automatically when the pin is inserted, thereby diminishing the clipping action at the point of intersection, so that the mass of hair seized is able to pass the point of intersection 40 into the upper loop without being pulled.

Owing to the fact that both the openings of the hair-pin always tend to close toward the point of intersection and in view of the absence of abrupt restrictions, projections, or 45 notches, the pin is prevented from binding against the mass of hair and entering with a jerk action, but will invariably slip in smoothly without disturbing the hair or removing the length of hair seized from its 50 proper position. Further, no tension is produced in the hair. The pin is therefore held securely in the hair, owing to the fact that after insertion the entire length of its resili- 55 ent arms exert a uniform pressure on the amply-held mass of hair, which is likewise distributed with perfect uniformity between

them. This effect is facilitated because as a result of the formation of the bent ends as much material as possible is seized. The secure hold of the pin is still further increased 60 because both its arms have a tendency to twist helically around their axis after insertion, thereby increasing the friction with which the arms hold the hair which has been gripped. As a result the pin is held securely 65 in the hair, even if it is polished quite smooth, so that it is unnecessary to roughen the arms of the pin or otherwise treat them for obtaining a better grip. The employment of a pin polished as smooth as possible is of course 70 highly desirable in order to facilitate its introduction and withdrawal. The withdrawal of this pin is not rendered more difficult in spite of its efficient resiliency, because the strain exerted by the pin is uniformly 75 distributed over the whole of the mass of hair seized by it. For this reason no single part of the mass of hair seized will be unduly strained, so that it will not be pulled or torn when the pin is removed. The ready and 80 smooth withdrawal of the pin is also facilitated owing to the fact that just in the same manner as during its introduction the diverging points, by reason of the pressure exerted upon them from the outside, cause the 85 pin to turn about its axis and the point of intersection to open. In inserting the pin, likewise, owing to the divergence of the ends of its arms the said rotation of the pin around its axis takes place without the ends of the 90 needles being forced apart to any considerable extent.

Several constructional forms of the novel hair-pin are presented by way of example in the accompanying drawings, in which— 95

Figures 1 and 2 illustrate a constructional form of the novel hair-pin in which both ends are bent toward each other in side and front elevation, respectively. Figs. 3 to 7 illustrate the manner in which this pin acts. Figs. 8 and 9 represent in two elevations a modified construction of the pin in which the end of one arm only is bent.

In the constructional form illustrated in Figs. 1 and 2 the two arms *a* and *b* cross each other at *c*. These arms proceed in a straight line from the bend and over the point of intersection *c* to the points *f* and *g* in proximity to their extremities, where they are bent in such a manner that in addition to being bent one toward the other they are bent obliquely 105 relatively to each other, and these obliquely- 110

set ends are directed in the same direction as that in which the resiliency is exerted; whereby the arms of the pin are held one against the other at the point of intersection *c*. Owing to this double bending of the two ends, to a certain extent they receive an oppositely-directed helically-acting twisting. Accordingly between the two arms of the pin there are formed apart from these oblique bends the two openings *d* and *e*, which constantly taper toward the point of intersection *c*.

In Figs. 3-5 it has been assumed that the pin is inserted through a plait of hair in the direction indicated by the arrow. In the first place, the points *h* and *i* seize (in the manner shown in Fig. 3) a certain quantity of material, which passes between the ends *f* and *g*. If the pin is pressed in farther with the finger, so that the material seized reaches the point of intersection *c*, the pin begins to rotate and assumes the position represented in Fig. 4, in which it has turned through approximately ninety degrees. If the pin is pressed in still farther, it turns through a further ninety degrees, so that it is given a position opposite to that shown in Figs. 1 and 3. If there is sufficient material in the position represented in Fig. 5, the opening *e* will also have become filled with it.

It is important that when first inserting the pin the points *h* and *i* should always seize as much material as possible and conduct it between the arms of the pin, but without these latter being quite opened out. Owing to the tendency of the pin to twist around its axis, the masses of hair are very securely held by the increased friction caused by the pressure of the arms.

It is likewise important that owing to the pressure of the hair contained in the loop *d* the bent ends *f* and *g* are pressed together in the manner of tongs, because by this means any self or unintentional retraction of the pin is effectually prevented. The closing of the ends *f* and *g* in the manner of tongs is still further assisted by the pressure of the hair on the parts of the arms *a* and *b* of the pin which constitute the opening *e* in the direction indicated by the arrows 1 and 2. Figs. 6 and 7 show the manner in which the hair slipping back is seized as by tongs by the ends of the arms of the pin, Fig. 7, thereby preventing self-retraction of the hair-pin. The action described is therefore threefold: First, fresh material is constantly seized by the bent ends; second, twisting of the pin during its introduction, assisted by the opposite twisting of the ends of the arms, and, third, closing of the open end of the hair-pin in the manner of tongs.

The same action is obtained when the hair-pin is constructed in the manner shown

in Figs. 8 and 9, in which only one arm is bent at the end and set obliquely relatively to the other. This construction does, however, modify the action to the extent that the end of that arm which is not bent serves to a certain extent as a pivot. This facilitates the introduction of the pin in the case of exceedingly thick hair.

In both constructional forms one of the arms may be made longer than the other, as indicated in Figs. 8 and 9, by the broken lines *i'*. The details of the pins may likewise vary in different ways. This is especially so as regards the size and shape of the upper loop *d*. The size of this upper loop is preferably smaller than that of the lower opening *e*, although this point is determined in accordance with the particular employment, as are likewise the size and strength. Again, the ends of the arms of the pin may be bent differently. The essential features are the tongs formation of the ends and oblique setting of the points relatively to each other, because by these means the action of the crossed arms of the pin is assisted.

Having now particularly described and ascertained the nature of my said invention and in what manner the same is to be performed, I declare that what I claim is—

1. A hair-pin, comprising a strand doubled upon itself to form arms lying adjacent to each other, the arms crossing at approximately their centers, the free ends of the arms being bent obliquely inward toward each other, and the tips of the arms being bent laterally in opposite directions.

2. The improved hair-pin herein described, having the opposite coöperating arms lying adjacent to each other and crossing approximately at their centers, the said arms having at their ends portions bent obliquely inward toward each other, and having the extremities of said inward-bent portions bent laterally in opposite directions, and to the opposite sides of the general plane of the arms of the pin whereby the insertion of the pin in the coil of hair tends to rotate said pin upon its longitudinal axis.

3. A hair-pin, comprising a strand doubled upon itself to form arms lying adjacent to each other, said arms crossing at approximately their centers, and the free end of one of the said arms being bent inward toward the other.

In testimony whereof I have hereunto set my hand, in presence of two subscribing witnesses, this 11th day of June, 1906.

HANS SUMMA.
